UNITED STATES PATENT OFFICE.

WILLIAM W. PECK, OF KALAMAZOO, MICHIGAN, ASSIGNOR TO PECK IRON AND STEEL WORKS, OF KALAMAZOO, MICHIGAN.

FOUNDRY SLIP-JACKET.

1,291,108.

Specification of Letters Patent. Patented Jan. 14, 1919.

Application filed October 21, 1918. Serial No. 259,078.

To all whom it may concern:

Be it known that I, WILLIAM W. PECK, a citizen of the United States, residing at the city and county of Kalamazoo, State of Michigan, have invented certain new and useful Improvements in Foundry Slip-Jackets, of which the following is a specification.

This invention relates to improvements in foundry slip jackets.

The main object of this invention is to provide an improved metal foundry slip jacket which is very durable, strong and rigid, and at the same time comparatively light and one which is economical to manufacture.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a perspective view of one embodiment of my invention.

Fig. II is a perspective view of another embodiment of my invention.

Fig. III is an enlarged detail horizontal section through one of the corners on a line corresponding to line 3—3 of Fig. I.

Fig. IV is a detail section similar to that of Fig. III before the wall plates and fillet are united at the corners.

Fig. V is a vertical section on a line corresponding to line 5—5 of Fig. I.

In the drawings similar reference characters refer to similar parts throughout the several views.

Referring to the drawing, the walls 1, 1 and 2, 2 of my improved slip jacket are plates of steel, preferably pressed steel. The corners of the plates are brought together with fillets 3 in the angles thereof and are integrally united throughout by fusing welds inside and out, the welds being acetylene or electric, both processes being used, which provide substantially unitary corners and thus, in effect, an integral structure.

In the embodiment shown in Fig. II I

provide a surrounding reinforcing frame 55 and handle member formed of angle iron pieces 4 mitered and fused welded at the corners, as at 5. These pieces 4 are disposed with their angles facing downwardly. This provides a rigid integral rectangular frame 60 which is slipped over the jacket. The jacket is preferably tapered and the frame is driven down firmly on the outer side thereof and the vertical arms of the frame secured by rivets 6, the rivets being countersunk within the jacket so as to leave its inner walls perfectly smooth. The horizontal arms of this frame are curved downwardly at their outer edges, as at 7, so that the embracing and reinforcing frame forms hand pieces.

In the embodiment shown in Fig. I short angle iron pieces 8 are riveted to opposite walls of the jacket with their angles facing downwardly by the hand pieces. The handles in this embodiment do not constitute reinforcing members. This jacket is welded at the corner by both the acetylene and electric welding process preferably the electric weld which provides a corner that is perfect, tight and through which no gas 80 can escape which would cause rusting and corrosion.

The advantages of this jacket over a riveted angle at the corner are that extreme accuracy is gained which is absolutely necessary for proper mold protection; further that the corners will always remain the same and cannot spread or pull apart.

My improved slip jacket is very strong and rigid, being capable of and well adapted to withstand rough usage, such as rough handling in the foundry or in transportation without being sprung or otherwise distorted.

Having thus described my invention, what I claim as new and desire to secure by Letters Patent, is:

1. In a foundry slip jacket, the tapered side walls of which are plates of steel, there being metal fillets in the corners, said wall plates and fillets being united throughout at the corners of the jacket by fusing welds inside and out providing an integral structure, and a frame embracing said jacket, said frame being formed of pieces of angle iron disposed with their angles facing downwardly and united at the corners by fusing welds providing an integral structure, the vertical legs of the frame being riveted to

the side walls, the horizontal legs thereof being curved downwardly and constituting handles.

2. In a foundry slip jacket, the side walls of which are plates of steel, there being metal fillets in the corners, said wall plates and fillets being united throughout at the corners of the jacket by fusing welds inside and out providing an integral structure, and
10. a frame embracing said jacket, said frame being formed of pieces of angle iron united at the corners by fusing welds providing an integral structure, the vertical legs of the frame being riveted to the side walls.
15. 3. In a foundry slip jacket, the side walls of which are plates of steel, said wall plates being united throughout at the corners of the jacket by fusing welds inside and out providing an integral structure, and a frame embracing said jacket, said frame being formed of pieces of angle iron united at
- 20.

the corners by fusing welds providing an integral structure, the vertical legs of the frame being riveted to the side walls.

4. A foundry slip jacket, the tapered side walls of which are plates of steel, there being metal fillets in the corners, said wall plates and said fillets being united throughout at the corners of the flask by fusing welds inside and out providing an integral structure, and angle iron members secured to the walls with their angles facing downwardly, the upper arms of said angle iron members being curved downwardly providing handles.

In witness whereof, I have hereunto set my hand and seal in the presence of two witnesses.

WILLIAM W. PECK. [L.S.]
